UNITED STATES PATENT OFFICE.

HARRY A. CROSSLEY, OF CLEVELAND, OHIO.

RADIATOR.

SPECIFICATION forming part of Letters Patent No. 437,680, dated October 7, 1890.

Application filed September 12, 1889. Serial No. 323,783. (No model.)

To all whom it may concern:

Be it known that I, HARRY A. CROSSLEY, a citizen of the United States, residing at Cleveland, in the county of Cuyahoga and State of Ohio, have invented certain new and useful Improvements in Radiators, of which the following is a specification.

This invention relates to steam-heating radiators, and has for its object to cheapen and facilitate the construction of tubular radiators; and it consists in the peculiar construction and combination of the parts comprising the radiator, substantially as hereinafter described, and pointed out in the claim.

15 In the accompanying drawings, Figure 1 is a side elevation of a radiator, partly in section, having a double base and showing my improved means of constructing and joining the circulating-pipes with the bases. Fig. 2 is an end elevation of the same. Fig. 3 is a 20 sectional view of part of a single base and a few circulating-pipes, on an enlarged scale, showing the construction and application of hollow perforated clamp bolts or plugs for securing the circulating-pipes to the bases. Fig. 25 4 is a cross-sectional view of a double base and a group of circulating-pipes, showing my new means of uniting the pipes to the bases.

A represents bases or base-pipes for carrying circulating-pipes, as B or B². The bases are provided on their top sides with a row of holes having countersunk holes for receiving the ends of said circulating-pipes. The bases are also provided on their under sides with a 35 corresponding row of holes directly opposite the top row. The bases are also divided by partitions *aa*, extending nearly to the bottom, dividing the interior into spaces, having two of said holes between each partition, except 40 at the ends.

B represents circulating-pipes, which may

be joined in pairs at their top ends by elbows, as *b b*, or they may be made in groups, as seen in Fig. 4, and have two general bottoms, as B², with necks, as *b²*, for attachment to the bases, as represented. The inside of the lower open ends of the circulating-pipes B and the necks *b²* are screw-threaded.

C C represent hollow clamping bolts or plugs designed for securing the pipes B to the bases A. Their open ends are screw-threaded on the outside for screwing into the ends of the pipes B. Their closed ends have flanges, and their sides are perforated to allow steam to circulate into and through them. By the use of these hollow bolts or plugs the securing of the circulating-pipes to the bases is very readily, easily, and quickly done.

The circulating-pipes are set into the countersunk holes in the bases in pairs or in groups, with a suitable gasket or packing-ring, and the bolts are inserted through the opposite holes and then tightly screwed up into the ends of the pipes B, firmly uniting them to the bases, a gasket with the flange 65 on the end of bolts closing the lower holes. These are readily removed for repairs or other purposes.

What I claim, and desire to secure by Letters Patent, is—

The combination, with the bases of radiators, as A, having a row of countersunk holes in their top sides and a corresponding row of holes in their under or opposite sides, and the circulating-pipes, as B, interiorly threaded, of the hollow and perforated clamping bolts or plugs C C, exteriorly threaded, substantially as and for the purpose specified.

HARRY A. CROSSLEY.
